JAMES CORY, OF WAYNE, MICHIGAN.

Letters Patent No. 82,091, dated September 15, 1868.

IMPROVEMENT IN BUCKLES.

The Schedule referred to in these Letters Patent and making part of the same.

TO WHOM IT MAY CONCERN:

Be it known that I, JAMES CORY, of Wayne, in the county of Wayne, and State of Michigan, have invented a new and useful Improvement in Buckles; and I do declare that the following is a true and accurate description thereof, reference being had to the accompanying drawings, and to the letters of reference marked thereon, and being a part of this specification.

Like letters indicate like parts.

The object of this invention is to so construct a buckle, with two bails and two tongues, so that it will hold when being pulled upon in either a forward or backward direction.

The invention consists in a double buckle, with two bails, A, one cross-bar, B, and two tongues, C, projecting from and pivoted to the cross-bar, in opposite directions, the outer end of each resting upon the bails A.

By the use of this buckle, should a strap or rein of a harness break, it can instantly be repaired, thereby saving, many times, the necessity of splicing, and saving much trouble when on the road, and away from ordinary conveniences for repairs. I am aware that a buckle with two bails is in very common use, one bail being used for the tongue to rest upon, while the other is designed to act as a loop, to hold the end of the strap.

I base my claim upon converting a buckle with two bails into a double buckle, which will hold from either direction.

What I claim as my invention, and desire to secure by Letters Patent, is—

The arrangement of the tongue C and cross-bar B, in connection with the bails A, in such a manner that each tongue shall operate on its bail without any intermediate bar, substantially as and for the purposes set forth.

JAMES CORY.
